UNITED STATES PATENT OFFICE.

HENRY GIESSEL, OF WAPAKONETA, OHIO.

STAPLE-RECEIVING CLIP FOR CONCRETE POSTS.

No. S17,762.

Specification of Letters Patent.

Patented April 17, 1906.

Application filed March 6, 1905. Serial No. 248,720.

To all whom it may concern:

Be it known that I, HENRY GIESSEL, a citizen of the United States, residing at Wapakoneta, in the county of Auglaize and State 5 of Ohio, have invented certain new and useful Improvements in Staple-Receiving Clips for Concrete Fence-Posts; and I do hereby declare the following to be a full, clear, and exact description of the invention, such as 10 will enable others skilled in the art to which it appertains to make and use the same.

My invention relates to a novel construction in a staple-receiving clip for concrete fence-posts, the object being to provide a device 15 of this character which will enable staples to be driven into and withdrawn from such posts without in any way fracturing or otherwise affecting such posts; and it consists in the features of construction hereinabove fully described and claimed.

In the accompanying drawings, illustrating my invention, Figure 1 is a fragmentary central vertical section of a concrete fence-post having clips constructed in accordance 25 with my invention embedded therein, one of said clips being shown in side elevation and the other in central vertical section. Fig. 2 is a fragmentary detail horizontal section on the line 2 2 of Fig. 1. Fig. 3 is a section similar to Fig. 2, showing a modified form of construction.

Concrete fence-posts are rapidly taking the place of wood posts, particularly on farms, but while very advantageous by reason of 35 their great strength and durability have been unsatisfactory by reason of the difficulty experienced in fastening taut wires thereto.

My present invention is designed to obviate this difficulty by providing means for removably securing such wires, and to this end 40 I provide sheet-metal clips, preferably made of scrap sheet-steel or galvanized iron of relatively light gage. The said clips are formed from oblong blanks of substantially double the length of their width. In the ends of said blank I press or otherwise form grooves B, which are substantially pear-shaped, the ends of said grooves being disposed in closer proximity than the middle portion thereof—that is, the ends of said grooves converge. After forming said grooves B in opposite ends 45 of said blank A on one side thereof the same is bent midway between its ends to bring the grooved ends together, so that the grooves 50 register with each other and form a pear-

shaped passage, which is cylindrical in cross-section.

The middle portion of the blank is preferably bent to substantially cylindrical form, as at C in Fig. 2, the grooved ends forming flanges 60 abutting against each other and being so securely held in any convenient manner—such, for instance, as folding the corners D of said flanges over upon one of same, as shown in Fig. 1—such flanges being obviously further 65 held against relative movement by the surrounding concrete of the post E, in which the clip is embedded.

Instead of bending the middle portion of the strip to substantially cylindrical form the 70 same may be bent to T shape, as shown in Fig. 3.

My said device is embedded in the post when the same is formed in the mold in plastic condition, so that the free ends of the 75 flanges are flush with one face of the post or with the bottom of a recess or depression G in the latter. When the concrete has become set, the clip or clips will be rigidly held therein, and the fence-wire H can be then secured 80 to said post by means of a staple J driven into the passages formed by the grooves B, the ends of said staple being forced to follow the contour of such passage and being bent thereby to ogee curves, the free ends of said 85 staple overlapping in the bottom of the passage. The said recess or depression G serves to cause the fence-wire to be slightly bent to enter same, and such bend therein effectually prevents said wire from becoming slack. 90 Should it become necessary to renew the wire or again stretch the same, the said staple J can obviously be readily removed and a new staple inserted.

My said device is exceedingly cheap and efficient and serves to render concrete fence-posts suitable for all purposes. 95

I claim as my invention—

1. A clip for concrete fence-posts, comprising a member adapted to be embedded in the post and having one end disposed flush with one face of said post, said member being provided with a U-shaped passage having converging ends, the mouth of said converging ends being disposed in said end of said member which is flush with one face of said post. 100

2. A staple-receiving metallic clip for concrete fence-posts comprising a member adapted to be embedded in the post and having an enlarged inner end, one end of said member 105

being substantially flush with one face of said post, said member being provided with a substantially U-shaped passage adapted to receive the staple and having converging ends 5 the mouths of which are disposed in the end of said member which is flush with one face of said post.

3. The combination with a concrete or other composite fence-post, of devices embedded therein for receiving fastening devices for securing wires or the like to said posts, said embedded devices being provided with passages bent between their ends and having their mouths disposed in one face of 10 the post, said embedded devices each comprising a strip of sheet metal bent between its ends and provided at its free ends with grooves adapted to register with each other when said free ends are brought into contact 15 with each other to form the aforesaid passage.

4. The combination with a concrete or

other composite fence-post, of devices embedded therein for receiving fastening devices for securing wires or the like to said posts, said embedded devices being provided 25 with passages bent between their ends and having their mouths disposed in one face of the post, said embedded devices each comprising a strip of sheet metal bent between its ends and provided at its free ends with 30 grooves adapted to register with each other when said free ends are brought into contact with each other to form the aforesaid passage, said grooved ends being secured together.

In testimony whereof I have signed my name in presence of two subscribing witnesses.

HENRY GIESSEL
